UNITED STATES PATENT OFFICE.

RUDOLPH F. STEHLIK, OF CHICAGO, ILLINOIS, ASSIGNOR, BY MESNE ASSIGNMENTS,
TO AUTOMATIC ELECTRIC INC., OF CHICAGO, ILLINOIS, A CORPORATION OF
DELAWARE.

TELEPHONE SYSTEM.

Application filed May 19, 1924. Serial No. 714,188.

The present invention relates in general to telephone systems, but is concerned more particularly with telephone systems employing line finders, i. e., systems in which a 5 finder switch individual to a trunk connects that trunk to a calling line when a call is made.

One object of the invention is the production of new and improved circuit arrangements whereby the line finders are directed in their movements so that they do not need to test groups of lines during the primary movement and individual lines during the 15 secondary movement, thereby permitting the finders to be made much simpler mechanically and electrically.

Another object is the production of new and improved circuit arrangements whereby the individual line relays are eliminated and 20 their functions performed by a small number of common line relays.

A further feature of the invention relates to the provision of a new and improved high speed sending switch which transmits two 25 series of high speed impulses to a finder switch to set it upon the calling line under the control of the common line relays.

A further feature of the invention resides in the arrangement whereby two finder alloters are employed to enable a larger number 30 of finders than could be served by one allotter alone to be grouped together.

A further feature has to do with new and improved circuit arrangements whereby the 35 setting up of a wrong combination on the common line relays when two lines in different tens groups are calling simultaneously is prevented by removing battery from all other tens groups when a line in one tens 40 group is calling. This prevents the units designation of a second line from becoming confused with the units designation of the first line, as will hereinafter appear.

A special feature of this case resides in the 45 arrangement whereby the wipers of the finders are normally standing opposite the first level of bank contacts so as to eliminate the vertical movement of the shaft when a line terminating in the first level of the finders 50 is calling. In connection with this feature,

the necessary mechanical arrangements have been made to permit the off normal contacts to be operated whenever the shaft moves from its normal position, either vertically or in a rotary direction. 55

Another feature relates to the provision of circuit arrangements common to an entire group of finders for selecting one of two sets of wipers on each finder.

A further object relates to the production 60 of an improved and simplified cut-off relay, together with a mounting frame on which the cut-off relays of all lines served by one group of finders may be mounted, thereby permitting common units and tens bars to be used as the fixed contacts for the cut-off 65 relays.

There are a great many other objects and features, having to do for the most part with the circuit details, which, together with 70 the foregoing, will be understood best from a further perusal of the specification.

Referring now to the drawings comprising Figs. 1-10, inclusive, Figs. 1-4, inclusive, show, by means of the usual circuit diagrams, a sufficient amount of equipment in a system embodying the principles of the invention to enable the invention to be understood and its utility appreciated; Figs. 5-7, inclusive, show the mechanical details of the improved cut-off relay and the frame in which it is to be mounted; and Figs. 8-10, inclusive, show such parts of a switch mechanism as are essential to enable the arrangement for maintaining the wipers of the 85 switch opposite the first level of bank contacts and the new and improved arrangement for operating the off normal springs to be understood.

Fig. 1 shows the substations A and A' 90 whose lines terminate at the exchange in connector banks and also in the banks of the finder F, which is mechanically of the usual vertical and rotary type, having its bank contacts arranged in ten horizontal rows 95 with ten sets of bank contacts in a row, making one hundred sets of bank contacts. The switch has two complete banks, each served by a separate set of wipers, making two hundred sets of contacts instead of one hundred 100

sets. Consequently, the finder F is enabled to connect with any one of a possible two hundred lines.

Fig. 2 shows the secondary switch SS, which is individual to the finder F, and which is connected with the latter through the intermediate distributing frame IDF'. This switch is operated simultaneously with the finder F to select a first selector such as the first selector S. Mechanically, the secondary switch SS is of the well known rotary type whose wipers move in a forward direction only and are advanced upon the back stroke of the stepping magnet rather than upon the front stroke. The selector S is similar to the finder F, but has only one set of wipers instead of two.

Fig. 3 shows the tens relays 201-210, inclusive, which are common to all of the two hundred lines in the group served by the finder F, together with the common units relays 211-220, inclusive, which are common to the first hundred lines of the two hundred line group, and the common units relays 221-230, inclusive, which are common to the second hundred lines of the two hundred line group. These relays operate to start the sender shown in Fig. 4 and to control the number of impulses transmitted by the sender.

Fig. 4 shows the two allotters FA-1 and FA-2 which are used to preselect finders in the two groups of finders having access to the lines of substations A and A'. These finders are divided into two groups on account of the fact that there are more finders having access to the lines of substations A and A' than there are sets of bank contacts on one allotter. Accordingly, the two allotters FA-1 and FA-2 are provided and they are arranged to operate as one allotter, the circuit arrangements being such that only one allotted finder can be operated in case a finder is allotted by each of the finder allotters when a call is made. The finder allotters FA-1 and FA-2 are each mechanically similar to the secondary switch SS.

Fig. 4 shows also the sender which, upon a call being made, is controlled by the common line relays shown in Fig. 3 to transmit two series of directive impulses to the finder which is allotted by one of the allotters FA-1 or FA-2. Mechanically, the sender is similar to either of the finder allotters FA-1 or FA-2.

Referring now particularly to Figs. 5-7, inclusive, Fig. 5 is a front view of a section of the improved cut-off relay mounting frame; Fig. 6 is a view of the same section as seen from the right side of Fig. 5; and Fig. 7 is a top view of Fig. 5. This frame comprises essentially the mounting strips such as 401 and 402 on which the cut-off

relays, such as 405-408, inclusive, are mounted. The mounting strips 401 and 402 are punched from soft iron "stock", and the heel pieces or magnetic returns for the relays are a part of the mounting strips themselves. For example, the extension 416 of the mounting strip 402, seen more clearly in Fig. 6, serves as a magnetic return for the cut-off relay 407 which is secured to the mounting strip 402 by the machine screw 417. The heel piece 416 serves also as a mounting strip 75 for the jack springs 412 as well as a mounting strip for the armature assembly.

The spring carrying member 409 of the relay 407 is made of brass and is riveted to the soft iron armature 410. There is a 80 groove cut in the armature 410 so as to enable the pivot pin, secured in the ears of the member 413, to lie loosely between the armature and the member 409. The contact springs 411 and 418, which are connected respectively to the two conductors of a subscriber's line, are suitably mounted on the member 409 and are insulated therefrom. The spring 418 normally makes contact with the associated tens bar 404 and the spring 411 normally makes contact with the units bar 421. The assembly is held in its normal position by the spring 415 which may be seen best in Fig. 7. This spring, together with the armature pivoting member 413, is secured to the heel piece 416 by the screw 414. Apparently the screw 414 clamps the member 409 also. However, this is not true on account of the fact that the hole in the member 409 is slightly larger 90 than the head of the screw 414, as may be seen in Fig. 7. When the relay 407 is energized, the soft iron armature 410 is attracted, pulling the springs 411 and 418 out of engagement with the common bars 421 and 404. 95

In the present case, since there are two hundred lines served by one group of finders, there are twenty vertical units bars such as the units bars 421 and 422. The first ten units bars are associated with the first hundred lines and the second tens units bars are associated with the second hundred lines. The ten tens bars, such as 401 and 403, however, are common to the entire group of 200 100 lines. 110

It will be understood that the cut-off relay 4, Fig. 1, associated with the line of substation A, together with the cut-off relays of the other lines of the system, is mechanically of the type shown in Figs. 5-7, inclusive, and that the common tens and units conductors, for example, the conductors 233, 243, and 253, Fig. 3, correspond to the common tens and units bars, the bars 403, 404, 421, and 422, for example, of the mounting frame shown in Figs. 5-7, inclusive. 115

Referring now particularly to Figs. 8-10,

inclusive, which show views of the vertical and rotary switch mechanism of the finder F, Fig. 1, the new and improved arrangements shown therein will be described. The 5 cam 460, Fig. 10, is secured to the shaft 452 in such a way as to hold the shaft normally one step higher than its usual normal position so that the wipers remain opposite the first level of bank contacts.

10 The off normal lever 457, Fig. 8, which controls the off normal springs 458 is bent obliquely at its right hand end so that the so-called normal lever 453, carried by the shaft 452 and best seen in Fig. 9, moves out 15 of engagement with the lever 457 when the shaft is rotated one step, the lever being again engaged by the normal lever 453 when the shaft rotates back to normal. It goes without saying that the off normal lever 457 20 is disengaged by the normal lever 453 when the shaft is raised one step. Thus it will be seen that the off normal springs 458 are allowed to operate as soon as the shaft 452 is rotated one step or moved vertically one 25 step.

Referring now particularly to Figs. 1-4, inclusive, the detailed description of the operation will now be given. For this purpose it will be assumed that the subscriber at substation A, desiring to make a call, removes his receiver. When the receiver is removed at substation A, a bridge is placed across the line conductors 2 and 3. The positive line conductor 3 is, at this time, grounded 30 through the resistance 11, armature 6 of the cut-off relay 4 and its resting contact, conductor 8, the common units conductor 243, and the resting contact and armature 246. Accordingly, a circuit is closed over 35 the negative line conductor 2 and through armature 5 of cut-off relay 4 and its resting contact, conductor 7, common tens conductor 233, resting contact and armature 235, and the normally closed contacts controlled 40 by armature 236 for the third tens relay 203, the line of substation A being number 33 in the first group from the standpoint of the finders. The tens relay 203, together 45 with all the other tens relays, is connected to battery through the holding conductor 241, resting contact and armature 352, resting contact and armature 350, resting contact and armature 372, and resistance 310. Accordingly, the third tens relay 203 energizes 50 over the calling line with results to be pointed out hereinafter.

Before proceeding further, it may be pointed out that the conductors 7-10, inclusive, are shown as independent conductors merely for the sake of convenience, and that, as a matter of fact, the resting contacts of the armatures such as 5 and 6 of the cut-off relays such as 4 are common tens and units bars as shown in Figs. 5-7, inclusive.

55 Returning now to the operation of the sys-

tem, relay 203, upon energizing, disconnects ground at armature 237 from the third tens conductor 273, extending to the sender bank (thereby predetermining that the tens digit to be sent out subsequently will be the tens digit 2 which will raise the wipers of the allotted finder from their positions opposite the first level to a position opposite the third level of bank contacts); places battery 70 through the common impedance 280 on the common tens conductor 233 at armature 237'; and at armature 236 opens the locking chain extending to the right of itself and closes a local locking circuit for itself at the same time opening its own initial circuit. Relay 234, which is included in the locking circuit of relay 203, now energizes 75 and disconnects at its ten upper armatures the ten respective line relay branches from the associated common tens conductors, leaving all the common tens conductors open with the exception of conductor 233 which, as above pointed out, is connected to battery at armature 237' of relay 203. Relay 234 also closes at armature 238 an energizing 80 circuit for relays 244 and 254 in multiple. Relay 254, upon energizing, disconnects ground from each of the associated units conductors. However, since no line is calling in the second group this does not 85 produce any further result at this time. Relay 244, upon energizing, disconnects ground from each of the associated units conductors at its ten upper armatures, and at armature 245 connects relay 249 to the chain 90 locking circuit. Responsive to the removal of ground from conductor 243 at armature 246, the third units relay 213 energizes over the following circuit: From ground by way of the third units relay 213, normally closed 95 contacts controlled by armature 247, contacts 250, units conductor 243, conductor 8, contacts 6, resistance 11, the calling line and substation, armature 5 and its resting contact, conductor 7, the third tens conductor 233, armature 237' and its working contact, and impedance 280 to battery. Relay 213, 100 upon energizing, opens at armature 247 the locking chain circuit extending to the right of itself and closes a locking circuit for 105 itself, at the same time opening its own initial circuit. Relay 213 also disconnects ground from conductor 283 at armature 248, thereby predetermining that the units digit 110 to be sent out subsequently will be the units 115 digit 3.

Relay 249 is included in the locking circuit of relay 213 and it accordingly energizes, disconnecting the units relays of the first group. Relay 249 also closes at armature 251 a circuit for relay 257 which thereupon energizes and disconnects the units relays of the second group. The number of the calling line is now completely registered 125 and the common tens and units line relays 130

are all disconnected from the subscribers' lines, thereby preventing any interference with the registered number due to further calls.

- 5 Relay 257 also places ground upon start conductor 263 at armature 258, thereby closing a circuit through the resting contact and armature 337 of relay 315, Fig. 4, and armature 351 and its resting contact for start relay 321. Start relay 321 thereupon energizes; locks itself to start conductor 263 at armature 359 so as to prevent its circuit being opened by relay 315 or by relay 318; places ground on the locking conductor 311 at armature 360; disconnects test wipers 383 and 397 of the finder alloters FA-1 and FA-2 at armatures 356 and 357 from the stepping magnets 381 and 396, respectively; and at armature 362 places ground on wiper 384 of the finder allotter FA-1 through the resting contact and armature 386. This ground potential is extended through the first contact in the bank of wiper 384 and over the associated conductor 69 to relay 26 of the finder F. Relay 26 accordingly energizes and prepares the finder F and the secondary switch SS for operation by connecting up the common conductors 61 and 62 and 64-67, inclusive.
- 10 As a further result of the energization of start relay 321, Fig. 4, the secondary switch SS, Fig. 2, is started due to the operation of armatures 358 and 361 of the said start relay 321 in a manner to be pointed out hereinafter.

- 15 As a result of the above mentioned grounding of the locking conductor 311 by start relay 321, a circuit is closed through the resting contact and armature 348, and the first contact in the bank of wiper 303 and said wiper for the upper winding of relay 314 of the sender. Relay 314 thereupon energizes and closes at armature 334 a circuit through armature 341 and its resting contact for the lower winding of the two step relay 316. Relay 316 thereupon energizes part way only because of the fact that the lower winding is of a small number of turns of wire having a relatively high resistance.
- 20 Accordingly, only the locking contacts (marked "1") close, but the remaining contacts (marked "2") are not operated. Upon the closure of the first step contacts by armature 340, a locking circuit is closed for the upper winding of the relay 316 in series with the lower winding. This locking circuit is not effective at this time, however, owing to the fact that the initial circuit of the lower winding is still established. As a further result of the energization of relay 314, it prepares a locking circuit for itself and an impulsive circuit through the high speed interrupter 308 for the finder F at armature 333; opens a point in the normal
- 25 restoring circuit of stepping magnet 305 at

armature 332; and at armatures 330 and 331 connects up the high speed interrupter 307. Accordingly, upon the first closure of the interrupter 307, a circuit is completed for stepping magnet 305, which thereupon energizes and moves the associated pawl into engagement with the next notch in the wiper driving ratchet wheel, but does not move the wipers themselves.

30 Upon the next subsequent opening of the circuit at the interrupter 307, stepping magnet 305 deenergizes and advances the wipers 301-304, inclusive, one step. Wiper 303 opens the circuit of the upper winding of relay 314, and wiper 301 closes a locking circuit from its locally grounded bank contact through the resting contact and armature 342 and armature 333 and its working contact for the lower winding of relay 314, thereby maintaining relay 314 energized. This locking ground is extended to the interrupter 308. However, the interrupter 308 is open at this time, being affixed to the shaft of the interrupter 307. As a further result of the advance of the wipers of the sender, wiper 304 closes a circuit for pick-up relay 315, whereupon relay 315 energizes; prepares a restoring circuit for the sender at armature 336; and at armature 335 connects the interrupter 307 in multiple with interrupter 308, i. e., connects it to the same ground supply conductor, at the same time removing ground locally from interrupter 307. Since, as before stated, the interrupters 307 and 308 are being operated at a high speed so as to produce a given number of interruptions in the shortest allowable time, the interrupters 307 and 308 again close at practically the same time that the wipers 301-304, inclusive, arrive upon the second set of bank contacts responsive to the above mentioned deenergization of the stepping magnet 305. Therefore, since the circuit of pick-up relay 315 is not closed until wiper 304 arrives upon the second associated bank contact, pick-up relay 315 cannot start to energize until about the time the interrupters 307 and 308 close again. This does not cause any harm to result, however, owing to the fact that the circuit of the interrupter 307 is shifted by means of the make-before-break combination controlled by armature 335, relay 315 having energized completely before the closure of the interrupters is terminated.

35 Accordingly, at the end of this closure of the interrupters 307 and 308, they, as well as the lower winding of the relay 314, are supplied with ground only through wiper 301. Upon the second closure of interrupters 307 and 308, which interrupters close simultaneously, a circuit is closed through interrupter 307 for the stepping magnet 305 of the sender, which thereupon energizes but does not step the wipers, and a circuit is closed through interrupter 308, armature 339

100

105

110

115

120

125

130

and its resting contact, conductor 61, armature 49 and its working contact of relay 26, Fig. 1, for vertical magnet 31 of the finder F. Vertical magnet 31 thereupon energizes and raises the wipers 16-21, inclusive, of the finder F from their position opposite the first level of bank contacts to a position opposite the second level of bank contacts.

Upon the next opening of the interrupter contacts 307 and 308, stepping magnet 305 of the sender deenergizes and advances the wipers 301-304, inclusive, into engagement with the next set of bank contacts. Wiper 301 is moved out of engagement with its locally grounded contact and into engagement with the contact in which conductor 272 terminates. The associated relay 202 is not energized and therefore conductor 272 is grounded, maintaining the lower winding of relay 314 energized.

Upon the next closure of the interrupters 307 and 308, stepping magnet 305 of the sender and vertical magnet 31 of the finder F are again energized and the wipers of the finder F are raised by vertical magnet 31 from their position opposite the second level of bank contacts to a position opposite the third level of bank contacts.

Upon the next opening of the interrupters 307 and 308, stepping magnet 305 of the sender deenergizes and advances the wipers 301-304, inclusive, into engagement with the next set of bank contacts. Wiper 301 at this time engages the bank contact in which conductor 273 terminates. Since the ground potential has been removed from conductor 273 by the third tens relay 203, as hereinbefore pointed out, this latter operation opens the circuit of the lower winding of relay 314 and removes ground from the interrupters 307 and 308.

Since, as before pointed out, the interrupters 307 and 308 are operated at the maximum allowable speed, they close again at about the same time that the wipers 301-304, inclusive, arrive upon the set of bank contacts corresponding to the digit being transmitted, and, if it were necessary, as is the case with known senders of this general type, to operate a stop relay to open the circuit of the interrupters, the interrupters would operate magnet 305 of the sender and the vertical magnet of the finder F again before the stop relay could be energized to disconnect the interrupters. However, the next closure of these interrupters is ineffective owing to the fact that the wiper 301, which is supplying ground to these interrupters, engages an ungrounded contact when it arrives upon the contact corresponding to the digit being transmitted.

The arrival of wiper 301 upon the contact in which the ungrounded conductor 273 terminates, results also in the opening of the

circuit of relay 314. Accordingly, relay 314, which is only very slightly slow to deenergize to enable it to hold up while the wiper 301 is passing from one contact to another, deenergizes and disconnects its own lower winding and the interrupters 307 and 308 from the wiper 301 at armature 333; disconnects interrupter 307 from in multiple with interrupter 308 at armature 331; and at armature 334 opens the initial circuit of the two step counting relay 316, whereupon the locking circuit for the two windings in series becomes effective and the relay energizes completely; disconnects, at armature 341, armature 334 of relay 314 from the junction of its own windings and connects it instead to the junction of the windings of relay 317; at armature 342 disconnects the locking armature 333 of relay 314 from the tens digit test wiper 301 of the sender and connects it to the units digit test wiper 302, preparatory to the transmission of the units digit to the finder; and at armature 339 transfers the upper terminal of the interrupter 308 from the vertical magnet operating conductor 61 to the rotary magnet operating conductor 62. As a further result of the deenergization of relay 314, it closes at armature 332 a restoring circuit for magnet 305 in multiple with the pick-up relay 315. This circuit includes armature 336 of relay 315 and its working contact and the local interrupter contacts 306 of stepping magnet 305. Accordingly, stepping magnet 305 operates in a buzzer-like manner and advances the sender wipers to their normal position, at which point its circuit and the circuit of the pick-up relay 315 are opened due to wiper 304 passing off the last grounded bank contact.

Relay 315 now deenergizes responsive to the opening of its circuit; opens a further point in the restoring circuit of the sender at armature 336; and at armature 335 prepares the interrupter circuits for the transmission of the next series of impulses.

As a further result of the return of the wipers 301-304, inclusive, to normal, the previously traced circuit for the upper winding of relay 314, which includes the resting contact and armature 348 of relay 317, and the first contact in its bank and wiper 303, is again established. Accordingly, relay 314 again energizes and closes a circuit at armature 334 through armature 341 and its working contact for the lower winding of the two step relay 317, whereupon relay 317, being similar to relay 316, operates through its first step only and closes a locking circuit for itself at armature 347. This locking circuit is not effective immediately, however, on account of the fact that the initial circuit for the lower winding of the said relay is still established. As a further re-

sult of the energization of relay 314, it prepares a locking circuit for itself and an operating circuit for the interrupter 308 at armature 333, and at armatures 330 and 331 5 again connects up interrupter 307. Accordingly, stepping magnet 305 is energized upon the next closure of the interrupter 307 and is subsequently deenergized upon the following opening of the interrupter 307, therefore 10 by advancing the wipers 301-304, inclusive, one step. Wiper 302 is now brought into engagement with its locally grounded contact, thereby completing the locking circuit of relay 314 and placing ground upon the 15 lower terminal of the interrupter 308 through the working contact and armature 342 and armature 333 and its working contact. Wiper 304 of the sender also engages a grounded bank contact, closing a circuit 20 for the pick-up relay 315, which accordingly energizes and at armature 335 transfers the lower terminal of the interrupter 307 from ground locally to ground coming from the units test wiper 302, as hereinbefore explained. 25

Upon each of the three following closures of the interrupters 307 and 308, a circuit is closed by interrupter 308 for rotary magnet 30 of the finder F as follows: from ground 30 by way of test wiper 302, working contact and armature 342, armature 333 and its working contact, interrupter 308, armature 339 and its working contact, conductor 62, armature 48 and its working contact, and 35 rotary magnet 30 to battery. Responsive to the three closures of this circuit, rotary magnet 30 advances the switch wipers 16-21, inclusive, into engagement with the third set of bank contacts in the third level, which 40 was previously selected by the vertical magnet 31. The normally connected set of wipers (19-21, inclusive,) is now in engagement with the bank contacts associated with the line of substation A, and the alternate set of wipers (16-18, inclusive,) is in 45 engagement with the bank contacts associated with the line of substation A'.

As a further result of each of the three closures of the interrupters 307 and 308 last 50 mentioned, the interrupter 307 closes a circuit for stepping magnet 305 three times and the wipers 301-304, inclusive, are, accordingly, advanced three more steps. These wipers, therefore, come into engagement 55 with the fourth set of bank contacts at the end of this series of operations and the units digit test wiper 302 engages the ungrounded bank contact associated with conductor 283, from which ground was previously removed by the common units line 60 relay 218, Fig. 1, at armature 248. That being the case, the interrupters 307 and 308 are again rendered ineffective and relay 314 again deenergizes, and at armature 334 opens 65 the initial energizing circuit of the lower

winding of relay 317. When this occurs, relay 317 operates through its second step owing to its previously established locking circuit including both windings in series; disconnects ground from the first contact in 70 the bank of wiper 303 at armature 348 so as to prevent the pick-up circuit of the upper winding of relay 314 being again closed when the wipers of the sender are subsequently restored to normal the second time; 75 and at armature 350 attempts to remove battery from holding conductor 241. However, relay 323 is now energized by relay 324 as will be explained more fully hereinafter and, assuming that the secondary switch SS 80 has not yet found an idle trunk, test relay 322 has not yet energized, and armature 350 and its resting contact is shunted by the working contact and armature 376 and the resting contact and armature 375 in 85 series. As a further result of the energization of relay 317, it closes a point in the allotter "kick-off" circuit at armature 346; disconnects the lower windings of relays 385 and 390 at armatures 344 and 345 so as to 90 prevent them from being operated when the kick-off circuit is finally established; and at armature 349 closes a point in the "switch-through" circuit.

As a further result of the deenergization 95 of relay 314, it closes at armature 332 the previously traced restoring circuit through interrupter contacts 306 for the stepping magnet 305 of the sender, whereupon the wipers 301-304, inclusive, are again restored 100 to their normal position, whereupon the circuit of pick-up relay 315 is opened by wiper 304 and the said pick-up relay 315 deenergizes. The sender has now completed its operation and remains at rest. 105

Returning now to the point at which start relay 321 was energized, the secondary switch SS, Fig. 2, is started upon the operation of the armatures 358 and 361, as hereinbefore mentioned. Specifically, armature 361 closes the following circuit: From ground by way of armature 361 and its working contact, the lower winding of test relay 322, conductor 67, working contact and armature 42 of relay 26 of the finder F, 115 Fig. 1, conductor 54, stepping magnet 101, and the common interrupter 102 to battery. At the same time, armature 358 of start relay 321 connects the junction of the lower winding of test relay 322 and stepping magnet 101 of the secondary switch SS to test wiper 104 of the secondary switch SS through the resting contact and armature 365 of test relay 322, conductor 64, working contact and armature 45, and conductor 55. 120

The operation now depends upon whether the trunk terminating in the bank contacts upon which the wipers of the secondary switch SS are standing is busy or idle. In case it is idle, test relay 322, Fig. 4, ener- 125

gizes immediately over its circuit traced above, but the stepping magnet 101 of the secondary switch SS is not operated owing to the relatively high resistance of test relay 322, permitting the wipers 103-105, inclusive, to remain on the idle trunk. In the present case, however, it will be assumed that the trunk upon which the wipers of the secondary switch SS are standing is busy. In this case, test wiper 104 is in engagement with a grounded test contact, short circuiting the lower winding of test relay 322 and preventing it from energizing owing to the fact that the said test wiper 104 is connected to the circuit including the lower winding of test relay 322 and stepping relay 101 in series at a point between the two. Due to the ground potential encountered by test wiper 104, stepping magnet 101 is energized through the common interrupter 102 and advances the wipers 103-105, inclusive, step by step in search of an idle trunk.

When an idle trunk is reached, which trunk it will be assumed is the one comprising conductors 161-163, inclusive, and extending to the selector S, the wipers 103-105, inclusive, of the secondary switch SS are rotated no further on account of the fact that the test wiper 104 engages an ungrounded bank contact. Also test relay 322, Fig. 4, being no longer short circuited, energizes in series with stepping magnet 101 of the secondary switch SS upon the next closure of the common interrupter 102. Upon energizing, test relay 322 closes a locking circuit for its upper winding at armature 367; removes battery from the holding conductor 241 at armature 375, armature 350 having been operated previously by relay 317; disconnects the test wiper of the secondary switch SS from the junction of its own lower winding and the stepping magnet at armature 365 and connects the said test wiper to ground, thereby making the seized trunk busy immediately; and at armature 364 places ground on the negative line conductor 161 of the selector S through conductor 66, working contact and armature 43 of relay 26 of the finder F, conductor 53, and wiper 103, whereupon line relay 111 of the selector S, which is connected to conductor 161 at armature 127, energizes over conductor 161 and closes at armature 121 a circuit for release relay 112. Release relay 112 immediately energizes and places ground on conductor 162 at armature 122, thereby making the associated trunk busy locally and independent of the ground sent ahead from the finder F through test wiper 104. Relay 112 also prepares the switch for operation by operating armature 123.

As a further result of the energization of the said test relay 322, Fig. 4, a circuit is closed for the connecting relay 24 of the

finder F as follows: From ground by way of the working contact and armature 349 of the relay 317, armature 368 and its working contact, resting contact and armature 389, wiper 383 of the finder allotter FA-1, conductor 68, off normal contacts 27 of the finder F, armature 46 and its working contact, connecting relay 24, and resistance 25 to battery. Relay 24 thereupon energizes; locks itself to the grounded release trunk conductor 55 at armature 38; connects up the line wipers 19 and 21 to the line conductors 53 and 56 at armatures 36 and 41, respectively; and at armature 39 places ground on test wiper 20 of the finder F, thereby closing a circuit for cut-off relay 4. When this occurs, cut-off relay 4 energizes and disconnects conductors 7 and 8 from the line conductors 2 and 3 at armatures 5 and 6, respectively.

Returning now to the point at which test relay 322, Fig. 4, energized, the said test relay 322 closes at armature 366 a circuit for stepping magnet 381 of the finder allotter FA-1 as follows: From ground by way of the working contact and armature 366, working contact and armature 346, resting contact and armature 388, and stepping magnet 381 to battery. Responsive to the closure of this circuit, stepping magnet 381 energizes and moves the associated pawl into engagement with the next notch in the wiper driving ratchet wheel but does not advance the wipers 383 and 384.

As pointed out above, battery is removed from the holding conductor 241 at armature 375 of relay 322 upon the energization thereof. Responsive to this, relays 234 and 203, Fig. 3, deenergize, and relay 234 opens the circuit of relays 244 and 254 at armature 238, whereupon the said relays 244 and 254 deenergize. Relay 244, upon deenergizing, opens the circuit of relays 249 and 213 at armature 245, whereupon relays 249 and 213 deenergize, and relay 249 opens the circuit of relay 257 at armature 251. Accordingly, relay 257 deenergizes and removes ground from start conductor 263 at armature 258, whereupon start relay 321, Fig. 4, deenergizes. Before proceeding with the explanation of what occurs in response to the deenergization of start relay 321, it will be well to point out that the amount of time required for the said relay 321 to fall back responsive to the removal of the battery from the holding conductor 241 as described above, is sufficiently long to permit the line and release relays of the selector S to energize and to permit the connecting relay 24 of the finder F to energize and lock itself to the release trunk conductor 55, which is grounded by release relay 112 of the selector S over the associated release trunk conductor 162, all as hereinbefore described.

Upon finally deenergizing, start relay 321

disconnects ground at armature 362 from the wiper 384 of the finder allotter FA-1 and accordingly from conductor 69 upon which the wiper is standing. When this occurs, relay 26 of the finder F deenergizes and disconnects the common conductors 61 and 62 and 64-67, inclusive, from the finder F at armatures 49, 48, 45, 44, 43, and 42, respectively. As a result of the common conductor 66 being disconnected from conductor 53, the initial circuit of the upper winding of the line relay 111 of the selector S is opened, leaving the said line relay energized over the calling line, and, as a result of the common conductor 64 being disconnected from the release trunk conductor 55, the common finder controlling equipment no longer supplies ground to the said release trunk conductor 55, leaving it grounded only from the release relay 112 of the selector S. Relay 26 also disconnects the combined test and switching conductor 68, which is individual to the finder F, from relay 24 and connects it to ground locally, whereby the conductor 68 is maintained grounded in order to maintain the finder F non-selectable to the finder allotter FA-1 until the said finder F has been restored to normal.

As a further result of the deenergization of start relay 321, Fig. 4, it removes ground from the locking conductor 311 at armature 360, whereupon relays 316, 317, and 322 deenergize. Relay 317, upon deenergizing, closes at armature 344 a circuit for the lower winding of relay 385 as follows: From ground by way of the grounded test conductor 68, wiper 383, resting contact and armature 356, resting contact and armature 344, and the lower winding of relay 385 to battery. Consequently, relay 385 energizes; disconnects wiper 384 at armature 386 from the holding conductor 326; disconnects wiper 383 from the switching conductor 327 at armature 389; disconnects stepping magnet 381 from the "kick-off" conductor 328 at armature 388; and at armature 387 opens the circuit of the upper winding of relay 390, whereupon relay 390 deenergizes (assuming that the allotter FA-2 is not hunting, but is standing on an idle finder) and closes at armature 392 a circuit for the upper winding of relay 385 so as to maintain that relay energized after the circuit of its lower winding is subsequently opened. Relay 390 also connects wiper 398 to the holding conductor 326 at armature 391; connects wiper 397 to the switching conductor 327 at armature 394; and at armature 393 connects stepping magnet 396 to the "kick-off" conductor 328. Thus it will be seen that the finder allotter FA-1 has been completely cut out of service, except as regards its testing operation, which will be explained subsequently, and that the finder allotter FA-2 is now in

operating position so that the first finder in group #2 will be operated upon the initiation of the next call.

As a further result of the deenergization of relay 317, it opens the circuit of stepping magnet 381 of the finder allotter FA-1 by removing ground from the "kick-off" conductor 328 at armature 346 to permit the allotter to "kick off", whereupon stepping magnet 381 deenergizes and advances the wipers 383 and 384 into engagement with the next set of bank contacts.

The further operation depends upon whether the finder associated with the second bank contacts of the finder allotter FA-1 is busy or idle. If it is idle, nothing further happens and the wipers 383 and 384 remain upon the second set of bank contacts. However, assuming the second finder to be busy, a ground potential is encountered by wiper 383 on its second bank contact, and stepping magnet 381 energizes again through the resting contact and armature 356, armature 354 and its resting contact, and the interrupter contacts 382, and the wipers 383 and 384 are advanced step by step in search of an idle finder owing to the buzzer-like action of stepping magnet 381 which interrupts its own circuit at contacts 382.

As a still further result of the deenergization of relay 317, battery is again placed upon the holding conductor 241 at armature 350. The next call may now be registered as soon as it is made.

Returning now to the connection which the subscriber at substation A desires to establish, the next operation on the part of the calling subscriber is the manipulation of his calling device in accordance with the first digit in the desired number. He is informed that he may now do this by the so-called "dial tone" which he hears when his line is connected through to the selector S. This dial tone, generated by the buzzer 175, is superimposed on the ground lead of line relay 111 by the associated transformer. When the calling subscriber dials the first digit, the circuit of line relay 111 of the selector S is opened a corresponding number of times. Upon each opening of its circuit, line relay 111 deenergizes and closes at armature 121 a circuit through armature 123 and the slow acting series relay 113 for vertical magnet 118. By the operation of vertical magnet 118, the wipers 131-133, inclusive, of the selector S are raised step by step until they stand opposite the desired level of bank contacts. Relay 113 is energized in series with vertical magnet 118 and, being slow acting, maintains its armature attracted throughout the vertical movement. Upon energizing, series relay 113 prepares at armature 124 a circuit for the stepping relay 114, which is closed at off normal con-

tacts 120 and through the interrupter contacts of rotary magnet 119 upon the first vertical step of the switch. Accordingly, stepping relay 114 energizes; closes a locking circuit for itself at armature 125; and at armature 126 prepares a circuit for rotary magnet 119.

At the end of the vertical movement, slow acting series relay 113 deenergizes and completes at armature 124 the circuit of rotary magnet 119, whereupon rotary magnet 119 energizes and advances the wipers 131-133, inclusive, into engagement with the first set of bank contacts in the selected level. Near the end of its stroke, rotary magnet 119 opens the circuit of stepping relay 114, whereupon stepping relay 114 deenergizes and opens at armature 126 the circuit of stepping magnet 119, permitting stepping magnet 119 to deenergize and again close its interrupter contacts.

The further operation depends upon whether the trunk terminating in the first set of bank contacts is busy or idle. In case it is idle, switching relay 115 energizes immediately, seizing the trunk. Assuming the trunk to be busy, however, switching relay 115 is short circuited by the ground potential encountered on the busy test contact by test wiper 132 and does not energize. This same ground potential operates stepping relay 114 to close the circuit of rotary magnet 119 at armature 126, whereupon rotary magnet 119 energizes again, advancing the wipers 131-133, inclusive, into engagement with the second set of bank contacts. This alternate operation of stepping relay 114 and rotary magnet 119 continues in this manner until an idle trunk is reached, which trunk it will be assumed is the one comprising conductors 134-136, inclusive. When this idle trunk is reached, switching relay 115 is no longer short circuited and energizes in series with stepping relay 114. Stepping relay 114, however, is not operatively energized at this time on account of the relatively high resistance of switching relay 115. Upon energizing, relay 115 removes ground from armature 121 of the line relay 111 at armature 129, thereby opening the circuit of the slow acting release relay 112; opens the test circuit and prepares the holding circuit at armature 128; and at armatures 127 and 130 disconnects conductors 161 and 163 from the windings of line relay 111 and extends them by way of the wipers 131 and 133 and conductors 134 and 136 to the windings of the line relay associated with the seized trunk. This line relay and the associated release relay (not shown) energize and the latter places ground on the release trunk conductor 135, thereby closing a holding circuit for switching relay 115 before the slow acting release relay 112 has had time to deenergize.

Responsive to the manipulation of the calling device at the calling substation in accordance with the remaining digits of the desired number, the connection is completed in any well known or desired manner, and 70 upon the termination of the ensuing conversation, the subscriber at substation A replaces his receiver with the result that the release trunk conductor 135 of the trunk seized by the selector S is ungrounded in the 75 usual manner, removing ground from the release trunk conductor 162 of the selector S, whereupon relay 115 of the selector S and relay 24 of the finder F deenergize. Relay 24, upon deenergizing, opens the circuit of 80 cut-off relay 4 of the calling line at armature 39, whereupon relay 4 deenergizes, restoring conditions at the calling line to normal.

As a further result of the deenergization 85 of relay 24 of the finder F, a circuit is closed for release magnet 29 as follows: From ground by way of armature 142 and its resting contact of busying relay 141, Fig. 2, conductor 57, spring 51, spring 50, armature 47 90 and its resting contact, armature 40 and its resting contact, off normal spring 28 and its upper contact, and release magnet 29 to battery. Upon the energization of release magnet 29, the wipers 16-21, inclusive, of the 95 finder F are restored to normal position in the usual manner, whereupon the circuit of release magnet 29 is opened at off normal spring 28. As a further result of the restoration of the finder F to normal, ground is 100 removed from test conductor 68 at off normal contacts 27, rendering the finder F selectable again to the finder allotter FA-1.

In the selector S, switching relay 115, upon deenergizing responsive to the above mentioned opening of its circuit, closes at armature 129 a circuit for release magnet 116 which includes springs 107 and 108, armature 121 and its resting contact, armature 123 and its resting contact, and off normal 105 spring 117 and its upper contact. Release magnet 116 thereupon energizes, restoring the wipers 131-133, inclusive, to normal in the usual manner, whereupon its own circuit is opened at off normal spring 117. 110

The entire connection is now released and the apparatus involved therein is ready for use in another call.

In order to explain the feature having to do with the automatic selection of the wipers of the finders, such as F, it will be assumed that the subscriber at substation A' makes a call. The line of substation A', it will be remembered, terminates in the upper bank of the finder F. Accordingly, when 120 this subscriber calls, the normally connected wipers must be disconnected and the upper set connected up instead, the wipers of the finder F being brought into engagement with the same bank contacts when the sub- 125 130

scriber at substation A' is calling as they are when the subscriber at substation A is calling.

When the receiver is removed at substation A', a bridge is closed across the associated line conductors and consequently across the register relay control conductors 9 and 10 which are connected to the line of substation A' through the contacts of the associated cut-off relay. Conductor 9 is connected to the third tens conductor 233, which is the same conductor with which the corresponding conductor 7 of the line of substation A is connected, and conductor 10 is, at this time, grounded through the resting contact and armature 256 of relay 254. Accordingly, the third tens relay 203 energizes with the results hereinbefore pointed out. One of the results of the energization of relay 203, it may be pointed out, is that relay 234 energizes and closes a circuit for relays 244 and 254 in multiple. Relay 254, upon energizing, disconnects ground from the associated common units conductors of the group to which the line of substation A' belongs, ground being removed from conductor 10 at armature 256. Accordingly, the third units relay 223 energizes through the normally closed contacts controlled by armature 260, armature 259 and its resting contact, and over the calling line. Relay 223, upon energizing, opens the locking chain circuit at armature 260 and closes a local locking circuit for itself, at the same time opening its initial circuit at the normally closed contacts controlled by the said armature 260. Relay 223 also disconnects ground from the third units conductor 283 at armature 261, which is the same units conductor from which ground was disconnected by the third units relay 213 in the previously described call made by the subscriber at substation A. As a still further result of the energization of relay 223 it grounds the wiper switching conductor 262, which is extended to and joined to the common wiper switching conductor 65. This is done preparatory to operating the wiper switching relay 23 of the finder F when the proper time arrives, as will be hereinafter pointed out. The locking circuit of relay 223 includes relay 249, which relay accordingly energizes and, among other things, closes a circuit for relay 257 at armature 251, whereupon relay 257 energizes, and, among other things, places ground upon the start conductor 263 at armature 258.

Responsible to the placing of ground upon the start conductor 263, start relay 321, Fig. 4, energizes with the hereinbefore pointed out results, one of which is that it grounds at armature 362, wiper 384 of the finder allotter FA-1 through the resting contact and armature 386. Accordingly, wiper 384 extends ground through conductor 69 to re-

lay 26 of the finder F. Accordingly, relay 26 energizes and performs the functions hereinbefore described. One result of the energization of relay 26 is that it connects the common conductor 65 to relay 23 at armature 44. Since conductor 65 is now grounded through conductor 262 by the units relay 223, Fig. 3, as hereinbefore pointed out, relay 23 energizes and disconnects wipers 19, 20, and 21 and connects up wipers 16, 17, and 18 at armatures 32-35, inclusive, respectively. Relay 23 also prepares a locking circuit for itself at armature 33.

As a final result of the above energization of start relay 321, the secondary switch SS selects an idle trunk and the wipers of the finder F are raised opposite the third level of bank contacts and are then rotated into engagement with the contacts in which the lines of substations A and A' terminate all in a manner hereinbefore described. Then when the connecting relay 24 energizes, the locking circuit of the wiper switching relay 23 is completed at armature 37 and the wipers 16-18, inclusive, are connected up at armatures 36, 39, and 41, respectively. The cut-off relay associated with the line of substation A' is now energized over wiper 17 and disconnects the conductors 9 and 10 from the calling line. The calling line is now connected through to a selector such as S and the call may proceed in the usual manner.

In order to explain the feature having to do with the arrangement whereby the wipers of the finder F are not operated vertically but are immediately rotated into engagement with the calling line when the calling line terminates in the first level of the finder F, it will be assumed that a subscriber whose line (not shown) terminates in the first level of the finder F, makes a call. The conductor associated with this line which corresponds to the conductors 7 and 9 associated with the lines of substations A and A', respectively, is connected to the first tens conductor 231 instead of to the third tens conductor 233. The other conductor associated with the line in question, which conductor corresponds to the conductors 8 and 10 of the lines of substations A and A', respectively, is connected with the one of the units conductors, depending upon the set of bank contacts in which the line terminates. Accordingly, when a call is made over this line, a circuit is closed over the tens conductor 231 for the first tens relay 201 which accordingly energizes and, among other things, places ground on conductor 271, thereby closing a circuit immediately for the two windings of the two step relay 316, Fig. 4, in series. Relay 316, which otherwise does not energize until the vertical movement has been completed, now

- energizes and disconnects the interrupter 308 from the vertical magnet operating conductor 61 and connects it to the rotary magnet operating conductor 62 at armature 339.
- 5 Relay 316 also prepares a circuit for relay 317 at armature 341, and at armature 342 disconnects the tens wiper 301 of the sender and connects up the units wiper 302. Accordingly, when the sender is started, as it
- 10 is in the usual manner responsive to the energization of relay 201, the correct number of impulses is transmitted to the rotary magnet 30 of the finder F to bring the wipers into engagement with the calling line.
- 15 The off normal springs of the finder F are operated at this time owing to the improved mechanical arrangement shown in Figs. 8 and 9, which permits the off normal springs to be operated whenever the shaft is moved
- 20 from its normal position, either raised or rotated, as hereinbefore explained.
- With known systems of this general character, the numbers are likely to become mixed or "scrambled", so to speak, when two
- 25 subscribers are calling simultaneously. For example, in certain systems, if calls are initiated simultaneously on lines 12 and 21, the lowest tens digit 1 and the lowest units digit 1 are transmitted, making the composite number 11 which is not the number of either calling line. The way in which this and similar occurrences are avoided in the present system will now be explained.
- 30 Assuming that two subscribers in different tens groups removed their receivers simultaneously, or nearly so, two of the tens relays 201-210, inclusive, start to energize simultaneously. However, none of the units relays start to energize because they are all normally short circuited by the armatures of
- 35 relays 244 and 254. Regarding the tens relays, only one can energize completely and lock itself up, owing to the fact that each tens relay opens the locking circuit of each
- 40 of the following ones. The common cut-off relay 234 energizes an instant later, and disconnects all the common tens conductors, leaving only one tens relay locked up. Accordingly, battery is now removed from all
- 45 the tens conductors except the one associated with the locked up relay, battery being placed on such conductor through the impedance 280 and an armature of the locked up tens relay.
- 50 As pointed out hereinbefore, relays 244 and 254 energize as a result of the energization of relay 234 and remove ground from the common units conductors to permit any one of the common units relays to energize.
- 55 Now if battery were not removed from all the common tens conductors except the one associated with the energized tens relay, the units relay corresponding to the lowest units digit of any calling line in any tens group

would energize. However, since the tens conductor of the energized tens relay is the only tens conductor supplied with battery, only calling lines in the same tens group can operate units relays for the reason that, even though subscribers on other lines may have their receivers off, no battery is available for the other lines.

Assuming that two subscribers in the same tens group are calling, two units relays attempt to energize. However, only one units relay can energize completely and close a locking circuit for itself owing to the fact that each units relay, upon energizing, opens the locking circuit of the remaining units relays of a higher order than itself. A moment later, relay 249 energizes and disconnects the associated units conductors and closes a circuit for relay 257 which energizes and disconnects the associated units conductors, at the same time grounding the start conductor, as hereinbefore pointed out, to start the sender to transmit the correct registered number to the allotted finder.

The effect of an accidental ground on a line will now be considered. Considering first an accidental ground on the negative conductor 2 of the line of substation A, which may be considered typical of a ground on any negative line conductor, a circuit is closed over the associated conductor 7 and through the common tens conductor 233 for the common tens relay 203 which thereupon energizes and locks itself in the hereinbefore described manner.

As a result, relay 234, which is included in the locking circuit of relay 203, energizes and places ground on the timing conductor 240 at armature 239, thereby closing a circuit through armature 338 and its resting contact, the resting contact and armature 343, and the resting contact and armature 353 for the slow-to-pull-up relay 325. This relay is slow to pull up, in addition to being slow to fall back, owing to the fact that the copper collar is placed on the end of the core next to the armature instead of the more usual position on the opposite end of the core. By this arrangement, the lines of force generated by the flow of current through the winding of the relay must pass through the copper collar before they reach the armature, which causes a delay in the operation of the armature. Upon finally energizing, relay 325 prepares a circuit for the alarm buzzer 309 at armature 373, and closes at armature 374 a circuit for the similar slow-to-pull-up relay 324, the two relays being provided primarily in order to give a longer delay than can be provided for by one relay. Upon energizing, relay 324 completes at armature 370 a circuit for the buzzer 309 and at armature 372 removes battery from the holding conductor 241.

The buzzer 309 now operates to give an audible signal to an attendant that trouble exists in this unit.

Responsive to the removal of battery from the holding conductor 241, the locked up tens relay 203 and relay 234 deenergize and the latter removes ground from conductor 240 at armature 239, resulting in the subsequent deenergization of the slow acting relay 325 which opens the circuit of the buzzer 309 at armature 373 and opens the circuit of relay 324 at armature 374. After a slight interval, relay 324 deenergizes also and again places battery on the holding conductor 241 at armature 372. In case the ground on the negative conductor of the line of substation A is still present, the above operations are repeated over and over and the buzzer 309 is intermittently operated to attract the attention of the attendant who proceeds to take the proper steps to remove the line of substation A from service in any well known or desired manner. On the other hand, if the ground on the negative conductor of the line of substation A was merely a so-called "swinging" or "passing" ground, the tens relay 203 and relay 234 are not again operated after they are unlocked and are ready for service.

It may be well to point out at this time that in the case of a regular call, battery is not prematurely removed from the locking conductor 241, owing to the fact that the start relay 321, upon energizing, shunts armature 372 and its resting contact at armature 365 and its working contact before relay 324 has had time to energize.

Considering now the effect of a ground upon the positive conductor 3 of the line of substation A, which may be considered as typical of a ground on any positive line conductor, nothing happens responsive to the ground being accidentally placed on the positive line conductor 3 of the line of substation A, but, if special provisions were not made, this ground would act as a shunt for the corresponding units relay 213, Fig. 3, to prevent its energization in case some other line having the same units designation makes a call. However, the resistance 11, Fig. 1, is interposed between the positive line conductor 3 and conductor 8 which connects to the third units conductor 243, thereby preventing the units relay 213 from being short circuited by the accidental ground, except as regards a call on the line of substation A itself. There is a resistance similar to 11 associated with each line, thereby isolating each line in trouble due to ground on the positive conductor, leaving each unaffected line free to call regardless of the grounded condition on the other lines.

It may happen occasionally that one of the switches of any finder secondary link

becomes defective through constant wear and fails to operate correctly. Assuming first that the finder F is out of order and does not find the calling line, the sender completes its operation in the usual manner and goes through the process of placing ground on the switching conductor to operate the connecting relay 24 of the finder F, but, since the finder F has not found the calling line, the calling condition remains on the calling line and the next allotted finder is operated to find the calling line.

It may happen occasionally that the secondary switch SS fails to operate mechanically. In this case, if the circuit of stepping magnet 101 is intact and in case the secondary switch SS is standing upon an idle trunk when a call is made, this idle trunk is seized and the call goes through in the usual manner. Assuming, however, that the trunk is busy or that the circuit of the stepping magnet itself is open, the secondary test relay 322, Fig. 4, whose initial energizing circuit must include the stepping magnet 101, is unable to energize. Therefore, the hereinbefore described "switch-through" circuit is not completed at armature 368 of the test relay 322, and the connecting relay of the allotted finder does not operate. Also the usual "kick-off" circuit for magnet 381 of the finder allotter FA-1 or magnet 396 or the finder allotter FA-2, as the case may be, is not completed at armature 366 of test relay 322. Therefore, if special arrangements were not made to advance the finder allotter in use automatically and independent of test relay 322, that finder allotter would be tied up on the defective finder selector link. Accordingly, special arrangements have been made for automatically closing the "kick-off" circuit independent of test relay 322. Obviously, such auxiliary closing means must be timed so as to allow a sufficient amount of time for the secondary switch SS, or any other secondary switch which is being operated, to complete its operation so as to prevent a premature "kick off". This auxiliary "kick-off" circuit is closed at armature 369 and its resting contact of the slow acting relay 323. This relay is energized at armature 371 of the slow-to-pull-up relay 324, which relay is in turn operated by the slow-to-pull-up relay 325. This latter relay, as has been hereinbefore explained, is operated over conductor 240 from armature 239, Fig. 3, upon the initiation of the call. Relays 324 and 325 are provided, as hereinbefore pointed out, for the purpose of intermittently operating the buzzer 309 and automatically unlocking the register relays when a ground occurs on a negative line conductor. These same relays are made use of in bringing about the automatic kick-off, as will now be explained. It will be apparent that the three relays 325,

324, and 323 all energize one after the other in a reasonably short time after the initiation of a call. These relays are all slow to deenergize and the circuit of relay 325 is opened at armature 338 of the pick-up relay 315, which relay, it will be remembered, energizes at the end of the first step taken by the wipers of the sender at the beginning of the first digit. When relay 315 pulls up relay 325 starts to fall back, and, at the end of the time for which they are adjusted, the three relays 325, 324, and 323 fall back one after the other, and relay 323 finally completes the kick off circuit at armature 369, the other point in this circuit having been closed already at armature 346 of relay 317, the adjustment of the relays 323-325, inclusive, being such that the sum of the time required for the three to fall back is greater than the longest time required for the finder F and the secondary switch SS to complete their operations under normal conditions.

A further point that may be mentioned at this time is that, since the pick-up relay 315 falls back at the end of the first digit, it is necessary to open the circuit of relay 325 at another point before relay 315 falls back. Accordingly, the circuit of relay 325 is opened at armature 343 of relay 316 which energizes before relay 315 falls back and which remains energized throughout the remaining part of the operation.

It sometimes happens that a finder, the finder F for example, is operated by the common sender to bring its wipers into engagement with the bank contacts of a particular line at a time when the test contact of such line (which contact is engaged by the test wiper 17 or the test wiper 20, depending upon which set of wipers is in use) is grounded. This may be due to the fact that the calling line was called by a connector switch after the receiver was removed and before the finder arrived, or it may be due in certain infrequent cases to the fact that the finder operated incorrectly and, therefore, landed on a set of contacts belonging to a busy noncalling line. In any event, in case the test wiper in use of the finder F engages a grounded contact at the termination of the operation of the finder F, ground is extended through the resting contact (or working contact, as the case may be) of armature 34 and said armature, and armature 39 and its resting contact to the junction of relay 24 and resistance 25. Accordingly, the relay 24 is short circuited and is not able to energize and connect up the line wipers of the finder F when the common mechanism attempts to close a circuit for the said relay 24 as it does in the hereinbefore explained manner after the finder F and the secondary switch SS have both completed their operations. Accordingly, no circuit is closed over the conductors 53 and 56 for the line relay of

the selector switch seized by the secondary switch SS and no holding ground is placed on the release trunk conductor 55, and the finder F is automatically released as soon as the finder allotter FA-1 is advanced to the next set of bank contacts as it is in the hereinbefore described manner.

It sometimes happens during a busy part of the day that all trunks accessible to a particular group of secondary switches, for example, the group in which the secondary switch SS is located, becomes busy. When this happens, it is obviously undesirable to operate the finder F and the secondary switch SS needlessly and is likewise desirable that the finder secondary link be made busy so that another link to which idle trunks are available may be operated to complete any call which may arise in this group. The way in which this is done will now be explained. The make-busy relay 141, Fig. 2, is connected in a closed circuit in series with the resistance 144. However, relay 141 is normally short circuited by a ground potential applied to the common conductor 143 by each idle one of the selectors, such as S, accessible to the same group of secondary switches. For example, when the selector S is idle, ground is supplied to the common conductor 143 by way of the spring 107, the spring 108, resting contact and armature 129, armature 121 and its resting contact, armature 123 and its resting contact, and off normal spring 117 and its lower contact. Now when the selector S becomes busy (the same applies to each of the other selectors), ground is removed from the particular branch of conductor 141 that extends to this selector at armature 121 of line relay 111, and again at armature 123 of release relay 112 when it energizes. Also when the off normal spring 117 shifts upon the first vertical step, a further point in this circuit is opened and remains open until the selector S again becomes idle and is restored to its normal position. Accordingly, when all the selectors, such as S, are busy, ground is removed from conductor 143 at all points and relay 141, being no longer short circuited, energizes in series with the resistance 144. Upon energizing, relay 141, which has an armature and two contacts for each of the secondary switches, such as SS, in the same group, disconnects ground from conductor 57 and places ground on conductor 58, which is the test conductor of the finder F and the secondary switch SS and which extends to the bank of test wiper 383 of the finder allotter FA-1. Accordingly, stepping magnet 381 of the finder allotter FA-1 is operated in the usual manner to advance the wipers 383 and 384 out of engagement with the bank contacts associated with the finder F and into engagement with an idle finder secondary link.

It occasionally happens that all finders accessible to the finder allotter FA-1 or to the finder allotter FA-2, as the case may be, become busy. Arrangements are provided 5 for preventing the unnecessary operation of such allotters when this occurs. Considering the finder allotter FA-1, the automatic stepping circuit of its stepping magnet 381 includes the resting contact and armature 314 of the relay 319. Relay 319 is included 10 in a closed circuit which includes the associated resistance 312. However, the normally grounded conductor 63, which is individual to the finder allotter FA-1, is 15 connected to the junction of resistance 312 and relay 319, normally preventing relay 319 from energizing. Conductor 63 is normally grounded in each of the finders. For example, it is normally grounded in the finder F 20 through the lower contact of off normal spring 28 and said spring, resting contact and armature 40, resting contact and armature 47, springs 50 and 51, conductor 57, and the resting contact and armature 142 of the 25 make-busy relay 141. Now when the finder F becomes busy, the off normal spring 28 is shifted and ground is removed from conductor 63 and is not replaced until the finder F is restored to normal position again. Also, 30 if the make-busy relay 141 associated with the group to which the secondary switch SS belongs is energized, the circuit through which ground is supplied to conductor 63 by the finder F is opened. Accordingly, if 35 the finder F is busy due to its being actually in use or due to the fact that the associated secondary group is busy, it does not supply ground to conductor 63, and when all the finders accessible to the finder allotter 40 FA-1 are busy, ground is entirely removed from conductor 63, permitting relay 319, Fig. 4, to energize in series with resistance 312 and disconnect stepping magnet 381 from 45 test wiper 383 at armature 354. In the same way relay 320 energizes when all finders accessible to the finder allotter FA-2 are busy and disconnects stepping magnet 396 at armature 355.

In case neither of the allotters FA-1 and 50 FA-2 is standing on an idle finder, which condition may arise if all finders accessible to both allotters are busy or if both allotters are operating in search of idle finders, arrangements are effective to prevent the closure 55 of the circuit of start relay 321. It will be noted that when test wiper 383 of the allotter FA-1 is in connection with a grounded contact, a circuit is closed through the resting contact and armature 356 of start 60 relay 321 for the left hand winding of the shunt field relay 318. When either winding of relay 318 is energized alone, the armature of the relay is not attracted owing to the fact that the core of the other winding serves 65 as a magnetic shunt for the core of the ener-

gized winding. Therefore, when only one finder allotter is standing on an idle finder, relay 318 is not energized. However, when both finder allotters are standing on busy finders, both windings of relay 318 are energized and the said relay 318 operates; disconnects start relay 321 at armature 351; disconnects relay 325 at armature 353; and at armature 352 opens the holding circuit so as to unlock any register relays that might 70 happen to be locked up at this time. As soon as one of the finder allotters FA-1 or FA-2 finds an idle finder, either at the end of the hunting movement (if it is hunting) or as soon as one becomes available (if none were 80 available at the time of the energization of relay 318), relay 318 falls back to permit calls to be put through.

It may be pointed out that the reason that the holding circuit of the register relays is 85 opened at armature 352 of relay 318, as pointed out above, is to prevent the possible needless operation of a finder immediately following the termination of a busy condition on both allotters. For example, if both allotters are busy for some length of time, a calling subscriber might remove his receiver, wait for the dial tone, and, not hearing it, replace his receiver before a finder becomes 90 available. In this case, if the register relays 95 were permitted to energize and lock up, the registered number of such subscriber would be transmitted to the first finder to become idle, which would be a needless operation on account of the fact that the subscriber has 100 already replaced his receiver. Furthermore, a second subscriber might have his receiver off and his service would be delayed while the number of the first subscriber is being transmitted. However, as before pointed 105 out, such an occurrence is prevented by the opening of the holding circuit at armature 352 of relay 318.

In case an attendant needs to make some minor adjustment on the finder F, and 110 wishes to cut the finder F out of service while he is doing this, he removes the small pin that is lying between the spring 51 and the spring 50 and pushes the spring 51 into its alternate position with the tip of spring 115 52 in the slot (not shown) in the spring 51 at which point he inserts the pin between the springs 51 and 52 so as to hold ground on conductor 68 to cause the finder F to test busy to the finder allotter FA-1. On spring 51, breaking contact with spring 50, ground is removed from the common conductor 63 at this point. Accordingly, the conditions which arise when the finder F is 120 actually busy are simulated. Similarly, if an attendant wishes to make a minor adjustment on the selector S, he cuts the selector S 125 out of service by removing the pin associated with the springs 107 and 108 and by subsequently inserting the pin between the springs 130

106 and 107 in the same manner as described in connection with springs 51 and 52 of the finder F.

It may be pointed out at this time that, as 5 intimated hereinbefore, the finders, of which F is one, and the secondary switches, of which SS is one, are split up into groups as determined by the lines and trunks, respectively, to which they have access. For example, the finder F has access to the lines of 10 substation A and A', together with 198 other lines, making 200 lines in all. All the finders having access to these same 200 lines are considered as one group, although from the 15 standpoint of the allotters they are split into two smaller groups as hereinbefore explained. This, however, has nothing to do with the trunking arrangement now being described. In the same way, the finders having access to the next 200 line group of lines 20 are another group of finders, etc.

The secondary switch SS has access to a number of first selector trunks, of which the trunk extending to the selector S is one. As 25 ordinarily constructed the switch SS has access to twenty-five trunks, and all secondary switches having access to the same twenty-five trunks are considered one group. Similarly, the secondary switches having access 30 to the second group of twenty-five first selector trunks are the second secondary group, etc. Now, in order to weave the finder switches and secondary switches in all groups into one unitary network, each finder 35 switch of a given group is cross connected on the intermediate distributing frame IDF' to a secondary switch in a different secondary group. For example, if there are thirty finders having access to the lines of substations A and A', and if there are thirty sec- 40 ondary groups, each finder is connected at the frame IDF' to a secondary switch in a different one of the thirty secondary groups, but if there are thirty finders in the group 45 as before, but only fifteen groups of secondary switches, two finders are connected to two secondary switches in each of the fifteen groups. This same arrangement is carried out for each of the primary groups.

50 The function of the intermediate distributing frame IDF, Fig. 1, will now be explained. It will be noted that the lines of substations A and A' are connected to the connector banks independent of the intermediate distributing frame, but are connected to the cut-off relay and the finder banks through the intermediate distributing frame. Accordingly, the number of these lines remains the same in the connector banks, re- 55 gardless of the connections at the intermediate distributing frame, but whenever it is desired, the outgoing traffic imposed upon the various groups of finders may be regulated and readjusted at will by merely

shifting the heavy calling and light calling 65 lines back and forth amongst the various finder groups until the traffic on the various groups is equally balanced.

It may be well to point out at this time that although the system has been described 70 as employing the special cut-off relay and mounting frame shown in Figs. 5-7, inclusive, in case it is so desired, ordinary cut-off relays of any well known type may be employed, in which case their contacts may be 75 multiplied together in the usual manner. It may be well to point out also that in case it is not desired to use a special mechanical construction for the finders such as F, the ordinary type of vertical and rotary switch may 80 be employed instead, in which case the sender and the cooperating tens relays may be arranged to step the finder to the first level when a call is originated in that level, instead of merely rotating its wipers as de- 85 scribed hereinbefore. Also it may be pointed out that applicant is well aware of the fact that numerous modifications of the system hereinbefore described may be made by those skilled in the art. Accordingly, applicant does not wish to be limited by any means to the exact details of the disclosure but wishes to be limited only by the appended claims.

What is claimed is:

1. In a telephone system, lines, a switch having access to said lines, relays common to said lines, means for closing a circuit through said relays and said relays including a calling one of said lines in series to operate 100 them to register the number thereof, and means for operating said switch under the control of said relays to establish connection with such line.

2. In a telephone system, lines, a switch having access thereto, registering means common to said lines, means for closing a circuit through said registering means and any calling one of said lines in series to register the number thereof, a sender, and means 110 for operating said sender under the control of said registering means to transmit the registered number to said switch to operate the same to establish a connection with the calling line.

3. In a telephone system, a link circuit comprising a directive finder and an automatic trunk hunting switch connected together, other similar link circuits, and a common apparatus comprising means for 120 transmitting impulses to said finders and means for controlling the hunting movement of said hunting switches.

4. In a telephone system, a directive finder and an automatic trunk hunting switch 125 paired together, other similar pairs, a common apparatus comprising means for transmitting impulses to any one of said finders

- and means for starting the hunting movement of the associated hunting switch, a connecting relay for each of said finders for connecting it to the associated hunting switch, and means for operating a connecting relay effective upon the completion of the operation of said transmitting means and of the operation of the associated hunting switch.
10. 5. In a telephone system, lines divided into two main groups, a switch having two sets of wipers and having access to the two groups of lines through the two sets of wipers respectively, a sender, means responsive to a call on any one of said lines for operating said sender in accordance with the number of such line to transmit that number to said switch, means responsive thereto for bringing the wipers of said switch into the position corresponding to the two lines bearing the transmitted number, and means common to all said lines for effecting the selection of the set of wipers associated with the group in which the called line is located.
15. 6. An impulse sender comprising a progressively movable step by step counting switch and an interrupter, a plurality of directive switches containing magnets operable by said impulse sender, an impulsive circuit including said interrupter, a wiper of said counting switch and a magnet of one of said directive switches, means for starting said counting switch and closing said impulse circuit through a live contact in the bank of said wiper to operate said magnet, and means for removing the potential from only one contact in the bank of said wiper to open said impulse circuit and stop the operation of said magnet when said contact is reached.
20. 7. In a telephone system, a group of switches divided into two sub-groups, a sender, two allotters associated with said sender, said allotters having access, respectively, to said sub-groups of switches, means for operating each allotter independent of the other to select an idle switch, means for connecting the sender with the allotter that has an idle switch selected in case the other allotter is searching and for connecting it with only one allotter in case each has an idle switch selected, and means controlled by said sender through the allotter to which it is connected for operating the selected switch.
25. 8. In a finder system, a plurality of lines, two allotters, a group of finders each having access to all of said lines and exceeding in number the capacity of either one of said allotters, and circuit arrangements whereby said allotters control the starting of said finders responsive to a call from any one of said lines.
30. 9. A group of finders, a relay in each finder, a group of common control conductors connected to contacts of said relays in multiple, and an allotter for controlling the energization of said relays separately to connect said conductors to the local circuits of said finders as required.
35. 10. In a telephone system, lines divided into groups, two character numbers assigned to said lines, the first character indicating the group and the second character indicating the position of the line in the group, finder switches having access to said lines, an impulse sender responsive to a call on any one of said lines for operating an idle finder in accordance with the first character of the number of that line to select the group and then in accordance with the second character to select the line, and means for positively preventing a finder from being operated in accordance with the first character of one line and the second character of another line under all conditions of calling.
40. 11. In a telephone system, lines divided into groups, a finder switch having access to said lines, said switch having as many levels of bank contacts as there are groups of lines, an impulse sender responsive to a call on one of said lines for operating said switch in one direction to select the group of the calling line and for operating it in another direction to select the calling line, and means for canceling the first movement of said switch when a call is originated in a line of the first group.
45. 12. In a telephone system, lines divided into groups, a finder switch having access to said lines, said switch having as many levels of bank contacts as there are groups of lines, means responsive to a call on one of said lines for operating said switch in one direction to select the group of the calling line and for operating it in another direction to select the calling line, means for canceling the first movement of said switch when a call is originated in a line of the first group, an off normal spring, and means for operating said spring when said switch is moved from its normal position to select a group and when it is moved from its normal position to select a line.
50. 13. In a telephone system, a vertical and rotary finder switch having a normal level over which the wipers are adapted to rotate without vertical movement thereof, a sender for transmitting vertical and rotary impulses to said switch responsive to a call, and means causing the omission of the vertical impulses in case the call is from a line terminated in the normal level.
55. 14. In combination, a plurality of relays, each having two movable springs, and two groups of substantially parallel bus bars, each bus bar in either group being substantially at right angles to each bus bar in the

- other group, and means for mounting said relays so that one spring of any relay may register with a bar in one group and the other spring may register with a bar in the other group. 5
15. In a telephone system, a group of tens relays, a group of units relays, contact bars connected to said tens relays, respectively, other contact bars connected to said units relays, cut-off relays, a line contact on each cut-off relay engaging a tens contact bar, and a second line contact on each cut-off relay engaging a units contact bar. 10
16. In a telephone system, a plurality of finder-secondary link circuits, each link circuit comprising a finder switch and a secondary switch, an equal number of groups of trunks, the secondary switches of the link circuits having access respectively to said 15 groups of trunks, an allotter for testing said link circuits and for connecting with an idle one, means for causing any link circuit to test busy to said allotter when the link circuit is actually busy and when all trunks 20 accessible to the secondary switch of the link circuit are busy, and means for preventing the hunting operation of the allotter when all the link circuits test busy. 25
17. In a telephone system, a sender, a plurality of backward hunting finder switches, means for preselecting an idle finder switch and for connecting said sender to it, means for operating said sender to set said finder switch, and means for preventing the operation of said sender when it is not connected 30 with a finder switch. 35
18. In a telephone system, lines, finder switches having access thereto, means including common relays for registering the number of any calling line and for transmitting said number to an idle finder to set it on such line, and means for preventing the operation of said registering relays when no finder is idle. 40
45. In a telephone system, a plurality of trunk lines, a switch associated with each, an allotter for allotting said trunk lines for use one at a time, means for initiating the operation of the switch associated with the allotted trunk line, means for advancing said allotter to the next trunk line responsive to the completion of said operation, and time controlled means independent of the last named means for advancing the allotter to the next trunk line in case said operation is not completed within a given time. 50
55. In a telephone system, a line, a line finder, relays controlled over both sides of said line in series for operating said finder to connect with said line, an alarm circuit, and means for closing said circuit responsive to the energization of only one of said relays. 60
21. In a telephone system, a plurality of lines, a relay connected to said lines in common, means for energizing said relay over any one of said lines, and a separate non-inductive resistance permanently connected to each line and between the line and said relay to prevent said relay being short circuited by a potential applied to one of said lines. 65
70. 22. A busy switch for automatic switches comprising two springs clamped between insulators, one spring being connected to ground and the other to a busying conductor, the said grounded spring being longer than the other and having an opening through which the other spring protrudes when the grounded spring is flexed, and a member co-operating with both springs near the ends thereof to hold the flexed spring in operated 75 position. 80
23. An electrical switch comprising three parallel insulated springs, the two outside springs being bent slightly in opposite directions at the ends thereof, the center spring being longer than the others and having an opening in alignment with the end portions of the other springs, and a member co-operating with the center spring and one of said other springs to hold the center spring in a flexed position in which the center spring intersects the plane of such other spring. 85
24. In a telephone system, a plurality of lines, a finder switch for connecting with a calling one of said lines, means for guiding said finder and for bringing it to rest in engagement with a line, and testing means for preventing connection with such line if it is busy. 90
25. In a telephone system, a group of lines comprising a plurality of basic line groups, finder switches having access to said lines, a plurality of wiper sets on said finder, the number of said sets depending on the number of said basic groups, means responsive to the initiation of a call by one of said lines for registering its number and for directing said finder to that number and means depending upon which basic group includes the calling line for selecting the wiper set 100 to be used. 105
26. In a telephone system, a group of lines comprising a plurality of basic line groups, a finder switch having access to said lines, a plurality of wiper sets on said finder, a set for each basic line group, means for registering the numbers of calling ones of said lines comprising a tens relay set common to the group and a units relay set for each basic group and means controlled by the units relay set for selecting the corresponding wiper set. 110
115. 27. In a telephone system, a group of lines, a plurality of groups of finder switches each switch having access to all of said lines, a plurality of allotter switches one per finder group, a sender and a register common to said lines, means responsive to a call from one of said lines for connecting said register 120
- 125

- and sender through one of said allotters to an idle finder switch in one of said groups, means operative thereby to preselect for the next call another allotter switch through which said register and sender will be connected to an idle finder, and means responsive to an all finder busy condition of one of said finder groups for causing said preselecting means to skip the allotter serving 10 said group.
28. In a telephone system, a group of lines, a register comprising tens relays and units relays common to said group of lines, said units relays being normally short circuited, circuits for said relays including calling ones of said lines, means for preventing the simultaneous operation of more than one of said tens relays, means responsive to the operation of one of said tens relays for removing the short circuit from 15 said units relays, and means for then energizing the units relay corresponding to the energized tens relay to register the number of a calling line.
29. In a telephone system, a group of lines, a register comprising tens relays and units relays common to said group of lines, said units relays being normally short circuited, circuits for said relays including calling ones of said lines, means for preventing the simultaneous operation of more than one of said tens relays, means responsive to the operation of one of said tens relays for removing the short circuit from 20 said units relays, and means responsive to the energization of said units relay for opening the circuits of said other units relays.
30. In a telephone system, a group of lines, a register comprising tens and units relays common to said group of lines, a normal short circuit for said units relays, circuits for said relays including calling ones of said lines, means for preventing the simultaneous operation of more than one tens 25 relay, means responsive to the energization of a tens relay for preventing subsequent energization of the remaining tens relays, means responsive to the operation of said tens relay for removing said normal short circuit from said units relays, means for energizing the units relay corresponding to the energized tens relay to register the number of the calling line, and means for preventing the subsequent energization of other units relays.
31. In a telephone system, a plurality of 35 lines, a group of finder switches having access to said lines, a group of selective switches, a step by step switch associated with each of said finders and having access to said selective switches, a register operable over a calling one of said lines to register the number thereof, a sender started through said register to direct said finder to said calling line, and means for preventing the operation of said register responsive to an all busy condition of said finders or selective switches.
32. In a telephone system, a plurality of lines, a group of trunks, a group of finder secondary link circuits, each having access to said lines and a secondary switch having access to said trunks, a register operable over a calling one of said lines to register the number thereof, a sender operable through said register to direct one of said finders to said calling line and means for preventing the operation of said register if there are no trunk circuits available to said associated secondary switch.
33. In an impulse sender comprising a counting switch and an interrupter, a directive switch having magnets operable by said sender, an impulsing circuit comprising said interrupter and one of said magnets, a two step relay containing contacts operable in the second step to substitute another of said magnets in said circuit, a plurality of closed branches for said circuit accessible to said counting switch, means for starting said switch and for energizing said relay in its first step and for completing said current through said switch and one of said branches, means included in said circuit for preventing the further operation of said relay, and means for opening one of said branches to open said impulse current to permit the further operation of said relay to make said substitution.
34. In a telephone system, a plurality of lines, a finder, means comprising two relays energized in series over said line for starting said finder, an alarm, means responsive to the energization of both of said relays for preventing the operation of said alarm and means responsive to the energization of only one of said relays for operating said alarm.

In witness whereof, I hereunto subscribe my name this 16th day of May, A. D., 1924.

RUDOLPH F. STEHLIK.
